GAME BOARD

Valdemar A. Hinzenberg, New York, N. Y.

Application May 4, 1950, Serial No. 9,708

Term of patent 3½ years

(Cl. D34—5)

To all whom it may concern:

Be it known that I, Valdemar A. Hinzenberg, a citizen of the United States of America, residing at New York, State of New York, have invented a new, original, and ornamental Design for a Game Board, of which the following is a specification, reference being had to the accompanying drawing, forming a part thereof.

The figure is a top plan view of a game board, showing my new design.

The rear of the board is plain. The board is of conventional thickness.

I claim:

The ornamental design for a game board, as shown and described.

VALDEMAR A. HINZENBERG.
